CLAIM

The ornamental design for a vehicle grille, as shown and described.

DESCRIPTION

FIG. 1 is a front perspective view of a vehicle grille in accordance with an embodiment of the present invention; and,

FIG. 2 is a left side perspective of the vehicle grille of FIG. 1, wherein a right side perspective view is a mirror image thereof.

The broken lines showing logos, vehicle body, vehicle wheels and light assemblies are included for the purpose of illustrating environment and forms no part of the claimed design.
